RECEPTACLE CLOSURE MEANS

Anton W. Konchan, Berwyn, Ill.

Application October 3, 1945, Serial No. 620,051

3 Claims. (Cl. 220—40)

1

The present invention relates to a receptacle closure means and will herein for convenience be explained as a closure for the gasoline tank of an automotive vehicle, although it is not so limited.

The present invention relates to closure members or means, which are connected and disconnected by relative twisting movement.

An important object of the present invention is to provide a closure cap which may be economically manufactured, in the main, from stampings.

An object of the present invention is to provide a closure cap which is applied and removed by twisting action and which is frictionally held in closed position.

Another object of the present invention is to provide novel means for applying frictional pressure between two relatively movable closure members for retaining the cap in closed position.

A further object of the present invention is to provide novel means for mounting the lugs of a cap for frictionally engaging the neck of a gas tank wherein the parts are rugged and capable of long-time use without breakage.

Another and still further object of the present invention is to provide novel means for causing frictional holding engagement between two relatively rotatable members.

The above, other and further objects of the present invention will be apparent from the following description and the accompanying drawings.

An embodiment of the present invention is illustrated in the accompanying drawing and the views thereof are as follows:

Figure 1 is a side elevational view of a neck and a cap connected in closed relation.

Figure 2 is a top plan view of the neck.

Figure 3 is a view, partially in elevation and partially in vertical section through the neck.

Figure 4 is a vertical sectional view through the cap showing details of construction, and showing relationship of parts when cap is in place on the neck.

Figure 5 is a vertical sectional view through the cap showing relationship of parts when cap is removed from the neck.

Figure 6 is a bottom plan view of the cap.

The drawing will now be explained.

The chosen exemplification of the present invention includes a neck A, which may be suitably attached to a closure, or receptacle, and a removable cap B.

The neck member A is shown as having a

cylindrical base 10 and a cylindrical neck 11, preferably of less diameter than the base, although the base 10 would not be used when the neck is formed as part of a receptacle.

5 The upper margins of the neck are turned to form two oppositely disposed inner flanges 12 and 13, which are circumferentially separated by gaps 14 and 15. The lower edge of each flange 12 is inclined downwardly as at 16, from its entrance end adjacent its gap, the inclined edge terminating in a shoulder 17.

10 The cap B comprises a shallow cup 18 having a substantially cylindrical wall 19 and a central portion 20. As illustrated in Figures 4 and 5 the lower surface of the central portion 20 will be designated as the outer surface and the opposite surface will be designated as the inner surface.

15 A movable member 21 is normally maintained in surface engagement with the outer surface of the central portion 20. This movable member 21 is formed as a shallow cup having a peripheral skirt 22 out of which are struck two lugs 23 and 24 which are curved in cross section.

20 The central portion 20 of cap B is provided with apertures 25, two being shown, through which pass pins 26 and 27 which at their lower ends are connected to the movable member 21 in any satisfactory manner so as to prevent separation.

25 Lying against the inner surface of the central portion 20 is a leaf spring C having a substantially horizontal central portion 28 and end portions 29 and 30 which are inclined downwardly, with their extremities bent to ride on the inner surface of the portion 20. The upper ends of the pins 26 and 27 are secured to the central portion 28 of the spring. When the parts are assembled the spring is tensioned so as to normally maintain the movable member 21 in engagement with the outer surface of the portion 20 of the cap.

30 The spring C is tensioned not only to maintain the movable member against the portion 20 of the cap but to resist movement of the member 21 away from the portion 20 which movement occurs when the lugs 23 and 24 are moved along the inclined edges 16 of the flanges of the neck A.

35 The passage of the pins 26 and 27 through the apertures 25 in the portion 20 prevents any movement of the movable member 21, with respect to the portion 20, in any other direction than axial.

40 The cap is designed to be manufactured at minimum cost. The parts are formed as stampings, except for the pins, and the assembly of the parts may be quickly accomplished. After the 45 movable member 21 has been mounted on the por-

50

tion 20 and the pins 26 and 27 fixed to the member 21 and spring C, the cover 31 is applied over the inner surface of the portion 20 with the cover flange overlapping the flange or wall 19 thereof, whereupon the lapping flanges are spun, thus permanently securing the cover 31 in place and completing the cap.

Before the member 21 is applied to the portion 20, the washer 34 is applied thereto, to position it between the lugs 23 and 24 and the outer surface of the portion 20.

The operation of the closure is as follows:

The cap B is applied to the open end of the neck A with the lugs 23 and 24 enterable in the gaps 14 and 15. The cap is then twisted so that the lugs 23 and 24 engage the inclined edges 16 of the flanges 12 and 13 of the neck and ride down the edges until the lugs engage the shoulders 17. During the twisting movement of the cap B to bring the lugs against the shoulders, the inclined edges 16 of the flanges causes movement of the movable member 21 away from the portion 20 of the cap. This movement is resisted by the tension of the spring C, the tension increasing as the cap is twisted. By reason of the fact that the surfaces of the lugs 23 and 24 which engage the inclined edges 16 of the flanges, are curved, wear is reduced to a minimum. Furthermore, the curved formation of lugs and the tension imposed on the movable member 21 by the spring C, assures that the cap B will remain in place, with the lugs against the shoulders 17, until the cap is manually twisted in the opposite direction.

As may be seen in Figure 4, when the cap B is in place on the neck A, the central or mid portion 28 of the spring C is bent towards the portion 20 and the end portions 29 and 30 are slightly straightened, thus exerting sufficient tension to hold the lugs 23 and 24 tightly against the flanges and shoulders to prevent accidental displacement due to vibration. Also, the member 21 is moved away from the portion 20.

Because of the fact that the movable member 21 is guided in axial direction only, wear imposed on the lugs is reduced to a minimum. Such reduction of wear prolongs the life of the cap, making replacements thereof a rarity.

There are caps on the market, in which the lugs constitute the end portions of a piece of spring metal riveted to a cap. Repeated applications and removal of such caps flexes the spring to an extent where it often breaks, or, being exposed to the atmosphere when removed, becomes rusted to a point where it is no longer effective to hold the cap in position on the neck.

In the present invention, by reason of the fact that the spring is concealed between the portion 20 and the cover 31 of the cap, protection is given the spring so that it is not subjected to rusting.

In order to open the interior of the receptacle to which the neck A is attached, to the atmosphere, a vent 32 is formed in the central portion 20 within the confines of the movable member 21, and, in fact, the member 21 has a registering vent 32a so that air within the receptacle may enter the space between the central portion 20 and the cover 31 and escape to the atmosphere through a second vent 33 formed in the central portion 20 outwardly of the exterior of the neck 11 of the member A.

A washer 34 surrounds the movable member 21 to lie between the outer surface of the portion 20 of the cap B and the neck to seal the joint between them.

It will be observed that the closure of the present invention is one which is economical to manufacture, and one which is sturdy in construction and will function satisfactorily for a long period of time.

The invention has been described herein more or less precisely as to details, yet it is to be understood that the invention is not to be limited thereby as changes may be made in the arrangement and proportion of the parts, and equivalents may be substituted, without departing from the spirit and scope of the invention.

I claim as my invention:

1. Closure means for a receptacle, including a receptacle neck having inturned portions forming circumferentially spaced flanges having inclined lower edges, a cap member for application to said neck having a part movable axially of said cap and having lugs engageable with the inclined edges of said flanges, a tensioned leaf spring mounted in said cap and connected by pins to said movable part, said pins passing through a portion of said cap structure to limit the movement of said movable part to axial movement only.

2. Closure means for a receptacle, including a receptacle neck having inturned portions forming circumferentially spaced flanges having inclined lower edges; a cap member for application to said neck having a part movable axially of said cap and having lugs engageable with the inclined edges of said flanges; a tensioned leaf spring mounted in said cap; and pins passing through the spring, a portion of the cap and through the movable part to connect said movable part to said cap member.

3. Closure means for a receptacle, including a receptacle neck member having inturned portions forming circumferentially spaced flanges having inclined lower edges, said flanges being circumferentially spaced to form gaps; a closure member including a body portion and a movable portion, said body portion comprising a top part and a bottom part, said parts having interengaged flanges to permanently connect them together, said movable part being formed with rigid lugs which are enterable through said gaps and which engage the inclined edges when said members are connected and relatively twisted; a tensioned leaf spring within said body portion; means passing through said spring, body portion bottom and said movable part to connect said movable part to said body portion and to prevent relative rotative movement of the body member and movable portion, the tensioning of said spring being such as to normally retain the movable portion against the bottom part of the closure and increasing as said lugs are moved along said inclined edges when said members are relatively twisted to connect the same.

ANTON W. KONCHAN.
